UNITED STATES PATENT OFFICE.

EMMA L. OEDER, OF ASHLAND, OREGON.

DESIGN FOR A DOLL.

Application filed April 28, 1925. Serial No. 18,248. Term of patent $3\frac{1}{2}$ years.

To all whom it may concern:

Be it known that I, EMMA L. OEDER, a citizen of the United States, and a resident of the city of Ashland, county of Jackson, and State of Oregon, have invented a new, original, and ornamental Design for Dolls, of which the following is a specification, reference being had to the accompanying drawings, forming part thereof, wherein—

Figure 1 is a side view, and Fig. 2, a three-quarter view in perspective of a doll illustrating my design.

I claim:

The ornamental design for a doll, as shown.

EMMA L. OEDER.
